Primary Examiner — Paula Greene

(57) **CLAIM**

The ornamental design for a “knife handle,” as shown and described.

DESCRIPTION

FIG. 1 is a front perspective view of my new handle

FIG. 2 is a top view

FIG. 3 is a bottom view

FIG. 4 is a rear view; and,

FIG. 5 is a diametric view.

The broken lines illustrating a blade are directed to environment and form no part of the claim. In FIG. 3 the small rectangular member with broken lines illustrate unclaimed features of the handle.
